ANDREW KERR, OF BELFAST, IRELAND.

RAILWAY SIGNALING.

1,242,701.

Specification of Letters Patent.

Patented Oct. 9, 1917.

Application filed September 6, 1916. Serial No. 118,765.

To all whom it may concern:

Be it known that I, ANDREW KERR, a subject of the King of Great Britain and Ireland, residing at Belfast, Ireland, have invented certain new and useful Improvements in and Relating to Railway Signaling, of which the following is a specification.

This invention relates to railway signaling and its object is to provide improvements in safety devices capable of giving an audible indication of the state of the signal to a train approaching the signal, so that, if, from any cause, the line semaphore signal cannot be seen, the driver of the train is made aware when it is dangerous to proceed, and it specifically relates to devices of this class, which are carried by the rail and in which the depression of a lever or the like by a passing train is caused to move a piston in a cylinder supported by the running rail so that air is compressed therein and discharged therefrom to actuate an audible signaling or warning device such as a whistle, horn or equivalent.

Under my invention the audible signaling apparatus of the class referred to is characterized by the combination, with an air compressing cylinder and a lever for operating the piston thereof both arranged in conjunction with the rail and adapted to move along therewith, of means whereby the piston in the air compressing cylinder and the lever for actuating same can be moved to and held at an "out of action" position when required and also by the fact that the piston which is returnable by spring means, after each stroke, has means whereby the piston and lever can be lowered out of active position without compressing the said spring means so that no spring force has to be overcome at the pulling of the apparatus to the "clear" position. As the whole arrangement is supported by the running rail there can be no movement of the rail relatively to the lever and cylinder, and the stroke of the piston in the cylinder will be unaffected by movements of the running rail due to sinking of sleepers or from any other cause. As a consequence the wheel flanges are prevented from getting between the running rail and the lever as there can be no movement of the rail away from the lever or vice versa.

On the drawings, which show one mode of constructing the apparatus, the same ref-

erence letters wherever repeated indicate the same parts.

Referring to the drawings, Figure 1 is an elevation of the lever and cylinder and Fig. 2 is a section on the line $x-x$ Fig. 1. Fig. 1^a shows a semaphore signal.

The air cylinder p^2 of the audible signaling apparatus is secured to the running rail r , being supported thereby and movable therewith, and the lever t is also supported by and movable with the running rail r being secured thereto through the medium of its fulcrum pin t^2 . The piston rod p^1 of the piston p is connected to the lever t at its free end t^1 and the piston and lever are pulled to their "ready for action" position (see dotted position of lever in Fig. 2) by the slackening of the signal wire a when it is desired the signal 1 (Fig. 1^a) should be allowed to move to the "danger" position by the weighted lever b . The movement of this lever causes the link b^1 to pull over the bell crank lever d^4 whereby the link d^2 , which is pivoted to one of the plates d^1 by a pin d^8 , is caused to turn these plates which are connected together by the cross pin d^5 and are centered, at d^{11} , to the depending arms p^3 of the cylinder p^2 . This movement causes a pull on links d^3 , which are pivoted to the plates d^1 , by pins d^{12} and to the sleeve d^6 , by pins d^9 so that the sleeve d^6 acts on the cushioning spring s and through it on the piston p^1 , whose reduced part slides through the sleeve and has a stop nut d^{10} at its end, and pushes it up until the treadle end t^1 is raised to the active position shown in dotted lines Fig. 2. The wheels of a passing train will depress the lever end t^1 and force the piston p down nearly to the bottom of the cylinder p^2 and this will happen each time the lever t is depressed by the wheel of a passing train so long as the sleeve d^6 is in the up position as in this position the treadle is by the action of the spring s returned to its "up" position after each down stroke. The piston p and lever t will be lowered to the "clear" or inactive position when the signal is pulled to "clear" the pull on the wire a causing a push on link b^1 thereby pushing back the bell crank lever d^4 whereby the link d^2 turns the plates d^1 so that the links d^3 push down the sleeve d^6 and, with it, the piston rod p^1 , the piston p and the end t^1 of the lever t . This arrangement makes it possible for the signalman to

move the treadle to "clear" with a minimum of effort as the piston p^2 has not to be pushed down by him against the action of the spring s , which being a powerful spring, 5 would involve considerable effort for the signalman to compress.

When the piston p compresses the air in cylinder p^2 the compressed air is discharged through an outlet non-return valve f and 10 then, through a suitable pipe f^1 , to a whistle f^2 , and, as the piston is forced upward by the spring s , after each depression, air is drawn in through a non-return inlet valve g .

The fulcrum end of the lever t may work 15 on antifriction rollers for the purpose of facilitating the turning movements of the lever about its fulcrum t^2 . y is an opening by means of which air can escape from and enter freely into the cylinder p^2 as the piston 20 ton p moves up and down. z is the end of a pipe for conveying lubricant to the cylinder.

Having now fully described my invention what I claim and desire to secure by Letters 25 Patent is:—

1. In audible railway signaling apparatus of the class described the combination with an audible signaling device operable by air under pressure, of means for compressing 30 the air, a lever for operating said means, the means and the lever being arranged in conjunction with a track rail so as to move therewith and means whereby the air compressing means and the lever can be retained 35 out of action when desired.

2. In audible railway signaling apparatus of the class described the combination with an audible signaling device operable by air under pressure, of a cylinder connected to 40 a track rail, a piston for forcing air from the cylinder to the device, means permitting air to pass from the cylinder to the device, a lever fulcrumed on the said rail and adapted to operate said piston, means for 45 bringing the lever into operative position and means for retaining it out of the operative position.

3. In audible railway signaling apparatus of the class described the combination with 50 an audible signaling device operable by air under pressure, of a cylinder connected to a track rail, a piston for forcing air from the cylinder to the device, means permitting air to pass from the cylinder to the device, 55 a lever fulcrumed on the said rail and adapted to operate said piston, a semaphore signal, means for operating the semaphore signal and means whereby when the semaphore signal is moved by the signalman to "danger" the said lever will be moved to the operative position and when 60 the semaphore signal is moved by the signalman to "clear" the said lever will be moved out of the operative position and when the semaphore signal is moved by the signalman to "clear" the said lever will be moved out of the operative position.

4. In audible railway signaling apparatus

of the class described the combination with an audible signaling device operable by air under pressure, of a cylinder connected to a track rail, a piston for forcing air from the cylinder to the device, means permitting air 70 to pass from the cylinder to the device, a lever fulcrumed on the said rail and adapted to operate said piston, resilient cushioning means for the piston and means whereby the said resilient means can be put out of action. 75

5. In audible railway signaling apparatus of the class described the combination with an audible signaling device operable by air under pressure, of a cylinder connected to 80 a track rail, a piston for forcing air from the cylinder to the device, means permitting air to pass from the cylinder to the device, a lever fulcrumed on the said rail and adapted to operate said piston each time it is depressed by a train wheel, spring means for forcing the lever upward after each depression and means for placing the spring out of action when desired.

6. In audible railway signaling apparatus 90 of the class described, the combination with an audible signaling device operable by air under pressure, of a cylinder connected to a track rail, a piston for forcing air from the cylinder to the device, means permitting air 95 to pass from the cylinder to the device, a lever fulcrumed on the said rail and adapted to operate said piston each time it is depressed by a train wheel, spring means for forcing the lever upward after each depression, and means, operable by the signalman, for placing the spring out of action when desired.

7. In audible railway signaling apparatus 105 of the class described the combination with an audible signaling device operable by air under pressure, of a cylinder connected to a track rail, a piston for forcing air from the cylinder to the device, means permitting air 110 to pass from the cylinder to the device, a lever fulcrumed on the said rail and adapted to operate said piston each time it is depressed by a train wheel, spring means for forcing the lever upward after each depression, a semaphore signal, means for operating the semaphore signal and means whereby when the semaphore signal is moved by the signalman to "danger" the said lever will be moved to the operative position and when the semaphore signal is moved by the signalman to "clear" the said lever will be moved out of the operative position and means, operable by the signalman, at the same time as he pulls the semaphore signal to the "clear" position, to place the said 120 spring means out of action.

8. In audible railway signaling apparatus of the class described, the combination with an audible signaling device operable by air under pressure, of a cylinder connected to 130

track rail, a piston for forcing air from the cylinder to the device, means permitting air to pass from the cylinder to the device, a lever fulcrumed on the said rail and adapted to operate said piston in one direction, a spring for moving the piston in the opposite direction, and means operable by the signalman for moving the piston in both directions.

10 9. In audible railway signaling apparatus of the class described, the combination with an audible signaling device operable by air under pressure, of a cylinder connected to a track rail, a piston for forcing air from 15 the cylinder to the device, means permitting air to pass from the cylinder to the device, a lever fulcrumed on the said rail and adapted to operate said piston in one direction, a spring for moving the piston in the opposite direction, and means, operable by the signalman, for putting said spring into 20 and out of action.

10 10. In audible railway signaling apparatus of the class described, the combination with an audible signaling device operable by air under pressure, of a cylinder connected to a track rail, a piston for forcing air from the cylinder to the device, means permitting air to pass from the cylinder to the device, a lever fulcrumed on 25

the said rail and adapted to operate said piston in one direction, a spring for moving the piston in the opposite direction, and means, operable by the signalman, for moving the spring into active position or into 30 inactive position.

11. In audible railway signaling apparatus of the class described, the combination with an audible signaling device operable by air under pressure, of a cylinder 40 connected to a track rail, a piston for forcing air from the cylinder to the device, means permitting air to pass from the cylinder to the device, a lever fulcrumed on the said rail and adapted to operate said piston in one direction, a spring for moving the piston in the opposite direction, and means, operable by the signalman, for moving the spring into active position or into 45 inactive position comprising a sleeve 50 slidable upon an extension of the cylinder and in which the spring is partly located and means for moving the sleeve relatively with the extension.

In testimony whereof I affix my signature 55
in presence of two witnesses.
